UNITED STATES PATENT OFFICE.

JAMES F. DAUT, OF WHEELING, WEST VIRGINIA, ASSIGNOR TO WHITAKER-GLESSNER COMPANY, OF WHEELING, WEST VIRGINIA, A CORPORATION OF WEST VIRGINIA.

ROOFING SHEET.

Application filed March 5, 1921, Serial No. 449,766. Renewed December 29, 1922.

To all whom it may concern:

Be it known that I, JAMES F. DAUT, a citizen of the United States of America, and resident of Wheeling, county of Ohio, and 5 State of West Virginia, have invented certain new and useful Improvements in Roofing Sheets, of which the following is a specification.

This invention relates broadly to sheet-10 metal roofing, and more specifically to a joint for such roofing.

The primary object of the invention is to provide a joint of the V-crimp type which shall be leak-proof and which shall possess 15 great strength and stability.

A further object is to provide a joint for sheet-metal roofing which not only has the members or parts thereof so arranged and related that they effectually guard against 20 leakage or seepage of water thereunder and are adapted to resist distortion or crushing from such strains as are ordinarily imposed thereon, but also a joint which involves a minimum number of bends or angles and 25 which, consequently, may be made conveniently and easily with dies of simple and economical forms.

With these and other objects in view, the invention resides in the features of construction which will hereinafter be fully described, reference being had to the accompanying drawings, in which—

Figure 1 is a view showing, in perspective, a roofing sheet constructed in accordance with my invention and forming joints at its opposite lateral edges with similar sheets; and—

Figure 2 is an enlarged section of the joint.

Referring to said drawings, 1 indicates a roofing sheet which is shaped along one of its lateral edges to provide a vertical supporting leg 2, a relatively narrow horizontal table or seat 3, and an inclined leg 4, 45 said seat 3 joining the upper ends of said legs 2 and 4. The opposite lateral edge of the sheet is shaped to provide an inclined leg 5, a horizontal table 6 and an inclined terminal leg 7, said table joining said legs 5 and 7.

Each sheet 1 is designed to form a close water-tight joint with an adjacent sheet of like form, the edge of one sheet having the two inclined legs being disposed in overlying or overlapping relation to the edge of

the other sheet which has but one inclined leg. In said relation the table 6 seats closely upon the table 3 with the leg 5 resting closely upon the inclined leg 4 of the underlying sheet. The inclined terminal leg 7 60 has its edge portion more or less closely overlying the body of the underlying sheet and disposed in closely abutting relation to the outer face of an upwardly pressed rib or bead 8 provided in said underlying sheet 65 at a spaced distance from the foot of the vertical leg 2 of the latter.

The upstanding rib 8 and the leg 7 cooperate in the formation of a barrier whereby the passage of water is in large measure 70 prevented. However, that portion of the underlying sheet which is located between said rib and the upright leg 2 constitutes the bottom of a trough 9 for the reception of seepage and whereby such seepage is 75 drained away from the joint. Furthermore, the chamber afforded between the legs 2 and 7 provides for a more or less free circulation of air whereby moisture which may collect in the trough is quickly dissipated. 80

Obviously, due to the fact that the legs 2 and 7 lie wholly out of contact one with the other, or out of overlapping relation, there is no possibility of the passage of water by capillary attraction to the level of the 85 tables.

The upright leg 2 with the closely engaging legs 4 and 5 form substantial supporting means whereby the joint is rendered capable of resisting strains imposed thereon either by the blows required to drive fastening nails through the engaged tables or by the weight of persons walking upon the roof.

A decided advantage possessed by the 95 structure described is that both the legs 5 and 7 of the joint are firmly braced, the former by the inclined leg 4 and the latter by the rib 8. Further, the formation of the joint members provides for more than ordinarily close nesting of the sheets for shipment.

What is claimed is—

A lapped joint for roofing sheets, comprising a lapped member composed of an 105 upright leg, an inclined leg and a narrow horizontal table connecting said legs, said inclined leg being formed along the terminal edge of the sheet, an upstanding rib in the sheet at a spaced distance from said up-

right leg, and an overlapping member formed on an adjacent sheet and composed of two inclined legs and a table connecting said legs, one of said legs of the overlapping member being in seated relation to the inclined leg of the lapped member, the table of the overlapping member being seated on the table of the lapped member, and the other leg of the overlapping member being disposed with its lower edge in closely abutting relation with the outer side of the rib

on the lapped member, said rib acting as a support for the last mentioned leg of the overlapping member and cooperating with the upright leg of the lapped member to 15 form a trough for the drainage of moisture.

In testimony whereof, I affix my signature in presence of two subscribing witnesses.

JAMES F. DAUT.
